(57) **CLAIM**

The ornamental design for a upper body garment, as shown and described.

DESCRIPTION

FIG. 1 is a front perspective view of a upper body garment showing my new design in an in-use configuration;

FIG. 2 is a front view thereof;

FIG. 3 is a top view thereof;

FIG. 4 is a bottom view thereof;

FIG. 5 a side view thereof; and,

FIG. 6 is a rear view thereof.

The long and short broken lines are unclaimed boundaries of the claimed design. It is understood that the claimed design may extend to these boundaries but does not include the boundaries.

The even-length broken lines shown in the drawings are directed to environment and form no part of the claimed design.
